UNITED STATES PATENT OFFICE.

MIKE BOLDIZS, OF STERLING, ILLINOIS.

LOCK.

1,077,120.

Specification of Letters Patent.

Patented Oct. 28, 1913.

Application filed November 6, 1911. Serial No. 658,694.

To all whom it may concern:

Be it known that I, MIKE BOLDIZS, a subject of the King of Hungary, residing at Sterling, in the county of Whiteside and 5 State of Illinois, have invented certain new and useful Improvements in Locks, of which the following is a specification, reference being had therein to the accompanying drawing.

10 This invention relates to locks, and the primary object of my invention is to provide a simple and durable lock embodying comparatively few parts that are inexpensive to manufacture, easy to assemble and 15 highly efficient for the purposes for which it is intended.

Another object of this invention is to provide a key operated lock for doors that has a locking bolt firmly held in an extended or retracted position, the bolt having a movement that is easily accomplished by the 20 operation of a key within the lock.

With the above and other objects in view, the invention resides in the novel construction, combination and arrangement of parts 25 to be hereinafter specifically described and then claimed.

Reference will now be had to the drawing, wherein:

30 Figure 1 is a rear elevation of the lock, partly broken away, Fig. 2 is a vertical sectional view of the same, and Fig. 3 is a perspective view of a detached locking bolt.

A lock in accordance with this invention 35 comprises a base plate 1 having one end thereof bent at right angles, as at 2 to close the end of a casing 3 riveted or otherwise connected, as at 4 to the plate 1. The plate 1 is rectangular and has openings 5 to accommodate screws or other fastening means 40 employed for securing the lock to a door.

The casing 3 is of less area than the plate 1 and the rear wall of said casing has an opening 6 alining with a key opening 7 in 45 the plate 1.

The right angular end of the plate 1 has a bolt opening 8 for a bolt 9 that is rectangular in cross section. This bolt has the under side thereof provided with a groove 50 10 and the inner end of said bolt, at one side thereof, is provided with a pin 11 that extends into a semi-circular slot 12 formed

in the casing 3. The inner end of the bolt 9 is normally supported by the pin 11 and the outer end thereof by the walls of the opening 8.

Arranged transversely of the casing 3 is a pin 13 and secured to said pin within the casing is a flat spring 14 that bears upon the upper side of the bolt 9.

Extending into the key opening 7 is a key 15 having the inner end thereof reduced, as at 16 to engage in the opening 6. The key 15 has a bit 17 provided with a slot 18, said slot providing clearance for a 65 ward 19 arranged upon the inner side of the casing 3. The bit 17 of the key 15 is adapted to engage in the recess 10, elevate and shift the bolt 9. As the bit engages the roof of the recess 10, the pin 11 is gradually 70 elevated in the slot 12, the walls of said slot guiding the pin 11 forwardly whereby the bolt 9 will be extended, as shown by dotted lines in Fig. 1.

It is thought that the operation and 75 utility of the lock will be apparent without further description, and while in the drawing there is illustrated a preferred embodiment of the invention, it is to be understood that the structural elements thereof 80 are susceptible to such variations as fall within the scope of the appended claim.

What I claim is:

A boltage mechanism for locks comprising an upwardly movable and a longitudinally shiftable oblong bolt rectangular in cross section at any point throughout its length and having its upper face uninterrupted from end to end and its lower face in proximity to its rear end formed with 90 a transversely extending rectangular groove of the same length as the width of the bolt, a pin projecting laterally from one side of the bolt at a point above the plane of the top wall of the groove and positioned near the inner corner of one side of the bolt and adapted to extend into a slot in the bolt casing whereby the inner end of the bolt is supported when normal and further constituting guiding means for the bolt when 95 shifted upwardly, a downwardly extending and rearwardly projecting curved spring having its forward end fixed and its rear end turned from and normally engag-

ing the top of the bolt for maintaining the latter in a normal position, the upward movement of said bolt being against the action of said spring, combined with a key 5 capable of engaging the walls of the groove for moving the bolt upwardly and for further longitudinally shifting the bolt.

In testimony whereof I affix my signature in the presence of two witnesses.

MIKE BOLDIZS.
